LEROY WYANT, OF CHICAGO, ILLINOIS, ASSIGNOR TO THE UNION SWITCH & SIGNAL COMPANY, OF SWISSVALE, PENNSYLVANIA, A CORPORATION OF PENNSYLVANIA

SLOW RELEASE LOCK FOR RAILWAY SWITCHES

Application filed January 26, 1932. Serial No. 588,925.

My invention relates to slow release locks for railway switches.

I will describe two forms of slow release locks embodying my invention, and will then point out the novel features thereof in claims.

In the accompanying drawings, Fig. 1 is a top plan view showing a railway switch S provided with one form of slow release lock embodying my invention. Fig. 2 is an enlarged sectional view taken on the line II—II of Fig. 1. Fig. 3 is an enlarged sectional view taken on the line III—III of Fig. 1. Fig. 4 is a top plan view showing another form of slow release lock embodying my invention, certain of the parts being broken away or removed to more clearly illustrate the construction.

Similar reference characters refer to similar parts in each of the several views.

Referring first to Fig. 1, the reference characters 1 and 1^a designate the stock rails, and the reference characters 2 and 2^a designate the movable switch points of a railway switch S of the usual and well-known construction. The switch points 2 and 2^a are connected together for simultaneous movement by a head rod 3 and a lock rod 4, and are arranged to be moved to their normal and reverse positions by means of an operating rod 5 which is connected at one end to the head rod 3, and at the other end, to a switch operating device 6. The switch operating device 6 may be of any preferred construction, and as here shown is actuated by manually operable throw lever 7.

The lock rod 4 extends underneath the rail 1 and cooperates at its free end with a suitable switch locking and indicating device A. As here shown, the device A is similar in all respects to that described and claimed in Letters Patent of the United States No. 1,450,331 granted to W. P. Neubert on April 3, 1923, and it is believed, therefore, that for purposes of the present disclosure, the following brief description of the construction and operation of the device A will be sufficient.

Referring particularly to Fig. 3, the device A comprises a casing 8 having a tail like projection 9. The main part of the casing is provided with a removable cover 8^a, and the

tail like projection 9 is provided with a cover plate 9^a. Formed in the tail like projection 9 is a transverse slot 10 which receives the lock rod 4, and formed in the cover plate 9^a is a rectangular longitudinally extending slot 11 which receives a locking plunger 12. The locking plunger 12 is movable between a locking and an unlocking position, and when the plunger is moved to its locking position, in which position it is shown in the drawings, it enters notches 13 in the lock rod 4 and locks the switch points in their normal positions. When, however, the locking plunger 12 is moved to its unlocking position, the plunger is withdrawn from the notches 13, and the switch may then be reversed at the will of the operator by means of the throw lever 7.

The reference character 14 designates a rocker arm which is pivotally mounted intermediate its ends on a pin 15 secured to the casing 8. The rocker arm 14 carries two rollers 16 and 17 journaled in such manner as to be free to rotate with respect to the arm. These rollers are adapted to cooperate with the locking plunger 12, and for this purpose, the undersurface of the plunger is provided with a recess 18 and the inner end of the plunger is chamfered at 19. When the plunger is in its projected or locking position, roller 16 enters the recess 18, and roller 19 engages an unrecessed portion 18^a of the under surface of the plunger. Under these conditions, the arm 14 is rocked to an extreme position in a clockwise direction, as viewed in Fig. 3. When, however, the plunger is moved from its locking position to its unlocking position, as soon as the plunger starts to move, the roller 17 is released by the chamfered end 19 of the plunger, and upon slight additional movement of the plunger, roller 16 rides out of recess 18, so that the rocker arm 14 is shifted in a counter-clockwise direction from the extreme position in which it is shown in Fig. 3, to its opposite extreme position. When the locking plunger 12 is restored to its locking position, the rocker arm is of course restored to the position shown in the drawings.

Pivottally attached to the right-hand end of the rocker 14 is a vertically extending

block 20 which is biased to an upper position by suitable means not shown in the drawings. The block 20 operates a circuit controller comprising two contact fingers 21 and 22 which are mounted in a block 23 of suitable insulating material secured to the casing 8. The lower contact finger 21 is fixed and is relatively rigid, whereas the upper contact finger 22 is comparatively flexible and has its free end extending between insulating blocks 24 secured to the upper end of the block 20. The parts are so proportioned that when the locking plunger 12 is in its projected or locking position, as shown in Fig. 3, the block 20 is forced downwardly against the action of its bias to a position in which contact 21-22 is closed. When the locking plunger 12 is moved to its unlocking position, however, the block 20 is released as soon as the chamfered end 19 clears the roller 17, and this block then rises due to the action of its bias, so that contact 21-22 becomes opened.

In accordance with my present invention means are provided for operating the locking plunger 12 in such manner that the locking plunger may be moved from its unlocking to its locking position quickly, but that a definite time interval of adjustable length is required to move the plunger from its locking to its unlocking position. As here shown, the means for operating the plunger comprises a horizontal rod 25, mounted in fixed guides 26 and 27, and having one end attached to the outer or free end of the locking plunger 12, and the other end operatively connected with a suitable timing device T which I will describe presently. Mounted on the rod 25 between the guides 26 and 27 is a fixed collar 28, a compression spring 29, a sleeve 30, and a fixed collar 31. The sleeve 30 is adapted to slide freely on the rod 25, and is operatively connected with a pivoted manually operable lever 32 by suitable means including a connecting link 33. The parts are so proportioned that when the manually operable lever 32 occupies the position shown, the sleeve 30 will engage the fixed collar 31 and will hold the locking plunger in its locking position. When, however, the lever 32 is rotated to its opposite extreme position, the sleeve 30 is moved toward the left on the rod 25, thus compressing the spring 29, and hence causing the spring to exert a force on the rod which moves the rod toward the left and the locking plunger 12 toward its unlocking position, the rate of movement of the parts under these conditions being determined by the timing device T as will now be made clear.

The timing device T may be of any suitable type and, in the form shown in Fig. 2, comprises a casing 35 having a cylinder 35^a extending therethrough. One end of the cylinder 35^a is closed by a cylinder head 36 and

the other end is closed by a cylinder head 37. A piston rod 39, which is fastened at its right-hand end to the free end of the rod 25, extends into the cylinder 35^a through a stuffing box 37^a and through a suitable hole 37^b in the cylinder head 37, and is attached, at its inner end, to a reciprocable piston 38 by means of a castle nut 40. The piston 38 is provided with an annular groove 38^b and with a plurality of holes 38^a which are arranged in a circle about the piston, and which communicate with the groove 38^b for at times permitting the passage of fluid through the piston as will be explained more fully herein-after. The side of the groove 38^b adjacent the holes 38^a is finished to form a valve seat, and constantly urged against this valve seat by means of a coil spring 44 is an annular valve 41 having an annular flange 41^a which fits within the adjacent end of the spring 44 to hold the valve in its proper position. Located in the casing 35 above the cylinder 35^a is a reservoir 43 which is constantly connected with the cylinder 35^a on the right-hand side of piston 38 through a port 42. The reservoir 43 is also constantly connected with the cylinder 35^a on the left-hand side of piston 38 through a port 49 in the reservoir wall and a passage in the cylinder head 36. As here shown the passage in the cylinder head 36 comprises two ports 46 and 48, a regulating valve 47 being interposed between these ports to control the flow of fluid through the ports. The regulating valve 47 may be of any preferred construction and, in the form here shown, comprises a rotatable cylindrical valve member 47^a attached to a valve stem 47^b. The valve member 47^a is provided with a plurality of restricted orifices 47^c, one or more of which may be brought into registration with the port 48 by turning the valve member. The reservoir 43 and cylinder 35^a are both intended to be filled with a suitable fluid such as oil, and in order to permit the insertion of the fluid into the reservoir and the cylinder, the reservoir wall is provided with a hole 45^a which is normally closed with a screw plug 45.

With the timing device T constructed in the manner just described, it will be apparent that when rod 25 is urged toward the left by the spring 29 in the manner pointed out hereinbefore, piston 38 will also be moved toward the left, and under these conditions, spring 44 will hold valve 41 closed, so that the fluid in cylinder 35^a in the left-hand side of piston 38 will be forced to flow through regulating valve 47. The rate at which fluid can flow through valve 47 is relatively slow, and it follows that the rod will be constrained to move at a relatively slow rate, so that a relatively long interval of time will be required to unlock the switch. When, however, rod 25 is moved toward the right, the pressure of the fluid in cylinder 35^a on the right-hand side

of piston 38 will open valve 41 and permit fluid to flow freely through the holes 38^a in piston 38 into cylinder 35^a on the left-hand side of the piston. The pressure exerted on valve 41 by spring 44 is comparatively small, so that very little pressure is required to open valve 41. It will be apparent, therefore, that very little force is required to move valve 41 toward the left, and that the resistance offered by the timing device to the movement of the rod 25 toward the right is therefore very slight.

Referring now to the modification illustrated in Fig. 4, as here shown, the lock rod 4 extends into a transverse slot 48 formed in the casing 49 of a locking and indicating device A¹, and cooperates with a longitudinally extending locking plunger 50 which is slidably mounted in the casing 49 for movement between a locking and an unlocking position. Also slidably mounted in the casing 49 directly below the locking plunger 50, and extending parallel therewith, is a rack bar 51. The rack bar 51 is provided with an upstanding pin 52 which enters a longitudinally extending slot 53 in the locking plunger 50, and is arranged to be reciprocated between two extreme positions by means of a manually operable lever 54 fixed to a shaft 55. The shaft 55 is journaled in suitable bearings secured to the casing 49, and has fixed thereto a pinion gear 56 which meshes with the rack bar 51. When the lever 54 occupies the extreme position shown, the rack bar 51 is moved to its right-hand extreme position, and under these conditions, the pin 52 engages the right-hand end of the slot 53 and holds the locking plunger 51 in its locking position, in which position it engages the lock rod 4 at the notches 13. When, however, the lever 54 is rotated through an angle of approximately 180° from the position shown to its opposite extreme position, the rack bar 51 is then moved to its left-hand extreme position, thus moving the pin 52 to such position that the locking plunger 50 is free to be moved to its unlocking position in which it is out of engagement with the notches 13 in the lock rod 4.

Operatively connected with the left-hand end of the locking plunger 50 is the piston rod 39 of a timing device T¹. The timing device T¹ is similar in all respects to the timing device T previously described with the exception that a coil spring 57 is interposed in the cylinder 35^a between the right-hand side of the piston 38 and the right-hand end of the cylinder. The parts are so proportioned that when the lever 54 is in the position in which it is shown in the drawings, so that the locking plunger 50 occupies its locking position, the spring 57 will be compressed. It will be apparent, therefore, that when the lever 54 is moved to its oppo-

site extreme position, the spring 57 will move the locking plunger to its unlocking position at a relatively slow rate which depends upon the adjustment of the valve 47 of the timing device T¹.

The locking plunger 50 is arranged to control a contact 58, indicated diagrammatically in the drawings, in such manner that this contact will be closed when the plunger occupies its locking position, but that, this contact will become opened as soon as the plunger has moved a short distance from its locking position toward its unlocking position.

In utilizing my invention, the contact 21—22 shown in Fig. 3 or the contact 58 shown in Fig. 4 will usually be employed to control a signal for governing traffic over the associated switch, and the parts will normally be so proportioned that, if the operator attempts to unlock the switch in order to reverse it after a train which is approaching the switch has passed the signal, a sufficient time interval will elapse before the switch actually becomes unlocked to permit the train to pass the switch, thus insuring that the switch cannot be thrown in a manner to cause a dangerous condition.

Although I have herein shown and described only two forms of slow release locks embodying my invention, it is understood that various changes and modifications may be made therein within the scope of the appended claims without departing from the spirit and scope of my invention.

Having thus described my invention, what I claim is:

1. In combination, a manually operated railway switch, a lock rod connected therewith, a locking plunger adapted to cooperate with the lock rod to lock the switch in one extreme position and movable between a locking and an unlocking position, resilient means for moving said locking plunger from its locking to its unlocking position, and a timing device connected with said locking plunger for regulating the time required for said resilient means to move said locking plunger from its locking to its unlocking position.

2. In combination, a manually operated railway switch, a lock rod connected therewith, a locking plunger adapted to cooperate with the lock rod to lock the switch in one extreme position and movable between a locking and an unlocking position, a spring, manually operated means including said spring for moving said locking plunger from its locking to its unlocking position, and means for controlling the speed of movement of said plunger.

3. In combination, a manually operated railway switch, a lock rod operatively connected with said switch, a locking plunger adapted to cooperate with said lock rod to

lock the switch in one extreme position and movable between a locking and an unlocking position, means for biasing said locking plunger to its unlocking position, a manually operable member reciprocable between two extreme positions, a pin and slot connection between said member and said locking plunger so arranged that when said member occupies one extreme position said locking plunger will be moved to its locking position but that when said member is moved to its other extreme position said locking plunger will be free to move to its unlocking position under the action of said biasing means, and means for controlling the rate of movement of said locking plunger in response to its bias.

4. In combination, a manually operated railway switch, a lock rod operatively connected with said switch, a locking plunger adapted to cooperate with the lock rod to lock the switch in one extreme position and movable between a locking and an unlocking position, said lock rod being provided with a slot, a spring connected with said lock rod in such manner that said locking plunger is biased to its unlocking position, a manually operable member reciprocable between two extreme positions and provided with a pin which cooperates with said locking plunger at said slot in such manner that when said member is moved to one extreme position said pin will engage one end of said slot and move said locking plunger to its locking position but that when said member is moved to its opposite extreme position said locking plunger will be free to move to its unlocking position in response to the bias of said spring, and means for controlling the rate of movement of said locking plunger in response to the bias of said spring.

In testimony whereof I affix my signature.
LEROY WYANT.
